UNITED STATES PATENT OFFICE.

WILLIAM C. CULBERTSON, OF GIRARD, PENNSYLVANIA.

ROTARY ENGINE.

SPECIFICATION forming part of Letters Patent No. 396,143, dated January 15, 1889.

Application filed March 1, 1888. Serial No. 265,833. (No model.)

To all whom it may concern.

Be it known that I, WILLIAM C. CULBERTSON, a citizen of the United States, residing at Girard, in the county of Erie and State of Pennsylvania, have invented certain new and useful Improvements in Rotary Engines; and I do hereby declare the following to be a full, clear, and exact description of the invention, such as will enable others skilled in the art to 10 which it appertains to make and use the same.

My invention relates to rotary motors or engines, and has for its object the provision of a device of this character which shall possess simplicity of construction combined with 15 efficient and easy action.

I provide a wheel or piston with inclined grooves in its opposite faces or ends and heads, on which the steam-chests are placed, and which carry valves which work in the grooves, 20 and are operated thereby to control the admission of steam from the chests. In front of the valves a continuous exhaust is provided, which not only permits but compels the discharge of the exhaust-steam at each revolution of the piston. The grooves in the wheel 25 are concentric; but their bottoms are inclined from lines flush with the faces of the wheel to a considerable depth, so that a gradually-decreasing area is assured as the piston revolves until the admission of steam is entirely cut off. The grooves in the opposite ends or faces of the wheel are disposed relatively to each 30 other in such manner as to avoid dead-points.

The following detailed description will more 35 fully explain the nature and construction of my invention.

The accompanying drawings illustrate what I consider the best means for carrying my invention into practice.

40 Figure 1 is a central longitudinal section of the device. Fig. 2 is a section of the head, steam-chest, and valve on line xx of Fig. 4. Fig. 3 is a perspective view of the wheel; Fig. 4, a side elevation of one of the stationary heads, and Fig. 5 a perspective view of one of the valves.

Similar letters of reference indicate corresponding parts in all the figures where they occur.

50 A A are the fixed or stationary heads, supported on any suitable base and affording

bearings for the shaft B, which passes through both of the said heads.

C C are the steam-chests provided upon the heads, having suitable steamways through them for the entrance of the live steam and the escape of the exhaust. In the steam-chest work valves D D, whose construction and functions will be explained further on.

E is the piston or wheel attached to and revolving with the shaft B. This wheel or piston is a plane circular block having annular inclined grooves e e formed in its opposite faces or ends. These grooves are concentric with the wheel; but their bottoms are inclined from a line flush with the face of the piston to a considerable depth at a point in the circumference close to the beginning. The slide-valves drop into these grooves at the deep ends, and the steam comes in contact with the 60 deep ends or abutments e' e' of the grooves, and, being confined by the slide-valves D, which ride upon the bottom of the grooves, it forces the piston around. The abutments e' e' of the grooves e e are placed diametrically opposite, so as to overcome the dead-points.

The valves D are constructed with a base-flange, d, upon the face of each valve, which flange not only serves the purpose of affording a hold for the steam, which thereby keeps 65 the valve pressed down into the groove, but also insures a space for the steam to enter between the abutment and the valve when the valve drops over the ledge of the abutment. The ports through the heads A A are of proper 70 form for the bases of the valves to completely close when forced up by the termination of the grooves at the shallow end. The induction or live-steam port g extends through the head A in front of each valve D, as shown in 75 Figs. 2 and 4 of the drawings. Suitable packing is placed between the ends of the piston and the heads to insure a steam-tight joint.

It is apparent that the construction of parts herein shown could be used for pumping purposes by suitable change of supply and discharge passages.

It will be perceived that as thus constructed, with the inclined grooves at opposite sides of the wheel or piston, an extremely simple 80 and compact engine is produced, which virtually consists of but three parts—the heads,

the piston, and the slide-valves. Moreover, the periphery of the piston being exposed, a driving-belt may be applied directly thereto, and thus the shaft-pulley be dispensed with, 5 further simplifying the engine.

It will be understood that any fluid motive power can be used to drive my engine, and it has been successfully operated with air.

Having thus described my invention, what I 10 claim, and desire to secure by Letters Patent, is—

1. In a device of the kind described, a wheel or piston having inclined valve-operating grooves in its opposite faces.

15 2. The combination of a wheel or piston having inclined grooves in its opposite faces with heads having sliding valves working in said grooves, as set forth.

3. The combination, with a wheel or piston having inclined grooves in its opposite faces, 20 of heads having valves adapted to work in said grooves and provided with base-flanges on one side thereof, as set forth.

4. The combination, with a piston or wheel having inclined grooves in its opposite faces, 25 heads having steam-chests, and sliding valves working in the grooves, of the wheel and exhaust-ports through heads back of the valves, substantially as set forth.

In testimony whereof I affix my signature in 30 presence of two witnesses.

W. C. CULBERTSON.
